SPRING WINDING MACHINE

Elmer W. Halvorsen and Arthur C. Nigro, Torrington, Conn., assignors to The Torrington Manufacturing Company, Torrington, Conn., a corporation of Connecticut

Application October 29, 1937, Serial No. 171,752

23 Claims. (Cl. 153—67)

The present invention relates to spring winding machines of the type adapted to produce what are commonly known as torsion springs, i. e., springs having coiled bodies of different lengths and diameters, with their projecting ends formed or bent to suit various purposes for which the springs may be used.

The object of the present invention is to provide a spring winding machine of the above indicated type, which is characterized by the provision of an improved mechanism for rotatably driving the spindle on which the springs are wound, whereby wide variations in the extent of the winding operation are obtainable, rotation of the spindle being controlled in accordance with a predetermined cycle which provides ample time for severing the wire stock following the winding of a coil and for forming the projecting ends of a spring, as desired. The machine of the present invention further provides for variations in the pitch of the springs produced and an improved mechanism for driving the feed rolls, so that exactly the right amount of wire will be fed past the winding spindle, for one end of the spring about to be wound, without interference with free movement of the stock between the rolls during the winding operation. The machine also provides improved means for severing the wire, for forming its projecting ends and for removing completed springs from the winding spindle. The above and other advantageous features of the invention will hereinafter more fully appear from the following description considered in connection with the accompanying drawings, in which:—

Fig. 1 is a view in side elevation of a spring winding machine embodying the invention.

Fig. 2 is a plan view of the machine shown in Fig. 1.

Fig. 3 is a vertical sectional view, on an enlarged scale, along the line 3—3 of Fig. 1.

Fig. 4 is a fragmentary sectional view on an enlarged scale, along the line 4—4 of Fig. 1, with associated parts partially in elevation, and partially in section.

Fig. 5 is a horizontal sectional view along the line 5—5 of Fig. 4, looking in the direction of the arrows.

Fig. 6 is a fragmentary view, showing a portion of the parts of Fig. 1 in different positions.

Fig. 7 is a fragmentary sectional view along the line 7—7 of Fig. 2, looking in the direction of the arrows.

Fig. 8 is a fragmentary sectional view along the

line 8—8 of Fig. 2, with associated parts shown in elevation.

Fig. 9 is a vertical sectional view along the line 9—9 of Fig. 2, on an enlarged scale.

Fig. 10 is a view in front elevation, on an enlarged scale, of the mechanism for cutting the wire and forming the end of a spring.

Fig. 11 is a vertical sectional view along the line 11—11 of Fig. 10.

Fig. 12 is a fragmentary view in front elevation, showing the mechanism for removing a completed spring from the arbor.

Fig. 13 is a vertical sectional view along the line 13—13 of Fig. 12, looking in the direction of the arrows.

Fig. 14 is a fragmentary view, illustrating an arrangement of gearing for reversing the direction of the winding spindle.

Like reference characters refer to like parts in the different figures.

Referring first to Figs. 1 and 2, the machine consists of a table 1, on which is mounted a spindle head 2 movable on suitable ways 3. A spindle 4 is rotatably mounted in the head 2, and is adapted to be driven by gearing 5, so as to have rotative movement imparted thereto in either direction. A lever 6 is adapted to impart back and forth movement to the head 2 on the ways 3, the gearing 5 and lever 6 being operable by mechanisms, hereinafter described.

The line of feed for the wire 7 is indicated by the arrow in Fig. 2, the wire 7 being fed by rolls 8 through a guide 9 at right angles to the axis of the spindle 4. In the formation of a spring, the wire 7 is first fed between a cylindrical arbor 10 and a pin 11 forming part of the spindle 4, see Fig. 3, and subsequent rotation of the spindle 4 causes the wire 7 to be wound in a coil on the arbor 10. The length of the spring thus wound is determined by the number of revolutions made by the spindle 4, while the pitch of the spring is determined by the amount of rectilinear movement imparted to the head 2 simultaneously with rotation of the spindle 4.

A spring S is shown as having been wound on the arbor 10 in Fig. 10, and after the winding operation, the spring is severed from the wire 7 by means of a tool 12 cooperating with the end of the wire guide 9. A second tool 13 cooperates with the tool 12 in order to form the projecting end of the spring just severed, in a manner hereinafter described. The completed spring is then removed from the arbor 10 by a stripping finger 14, after which the spindle 4 is retracted and comes to rest in a position with the space 55

between the arbor 10 and pin 11 in alignment with the wire guide 9. The rolls 8 then again feed a predetermined length of wire, to initiate another cycle of spring winding and forming operations.

Having thus described the general function and operation of the essential elements entering into the production of springs by the machine, there will next be described, in the order named, (a) 10 the spindle driving mechanism, (b) the pitch control mechanism, (c) the feed roll mechanism, (d) the wire cutting and end forming mechanism, and (e) the spring stripping mechanism.

Spindle driving mechanism

15 As best shown in Fig. 3, the spindle 4 is rotatably mounted in bearings 15 provided by the head 2. A bolt 16 extending through the spindle 4 cooperates with a threaded opening 17 in a tapered extension 10a of the winding arbor 10 to lock the arbor in position, so that in effect it forms part of the spindle 4. The outside of the spindle 4 provides elongated teeth 18 in mesh with the teeth of a driving gear 19 mounted on a shaft 20 located below the ways 3, on which the head 2 is moved. Therefore, the spindle 4 and arbor 10 are adapted to be rotatably driven simultaneously with rectilinear movement of the spindle head 2.

30 The shaft 20 carries a pinion 5' forming part of the train of gearing 5 shown in Fig. 1, which terminates in a gear 5''' mounted on a shaft 21 below the table 1. The shaft 21 carries a pinion 22, which is in mesh with teeth 23a provided at 35 the end of a segment 23 pivotally mounted on a shaft 24 supported by the machine base 25. The segment 23 is adapted to have a back and forth movement imparted thereto from a cam 26 mounted on a drive shaft 27, and the invention 40 contemplates an adjustable driving connection between the segment 23 and the cam 26. By this connection, the amplitude of movement of the segment 23 can be readily varied to so control the degree of rotation of the winding spindle 4 as to make it possible for the machine operator to very accurately determine the number 45 of convolutions in springs wound on the arbor 10.

As best shown in Figs. 1, 4 and 5, the segment 23 provides a track or raceway 28, which extends 50 at an angle to the pivotal axis of the segment 23, for a purpose which will later appear. The track 28 receives a roll 29 mounted on a stud 30 forming part of an adjusting block 31, slidably between ways 32 provided by one face of an arm 33, pivotally mounted on a shaft 34 extending beneath the table 1. The free end of the arm 33 carries a stud 35, on which is mounted a roll 36 received in the track 26a of cam 26. With 55 the parts occupying the position of Fig. 1, it is evident that the roll 36 will be nearest the axis of rotation of the cam 26, and that as the shaft 27 turns through one revolution, the cam roll arm 33 will have an oscillatory movement imparted thereto about its pivot shaft 34. This movement 60 of the arm 33 will be transformed into oscillatory movement of the segment 23 about its pivot 24 through the operation of the roll 29, and the amplitude of movement of the segment 23 will depend upon the position of the block 31 between the ways 32 on the arm 33.

In order to vary the amplitude of movement of the segment 23, and consequently the number of turns through which the spindle 4 is rotated as the segment 23 swings in one direction, an adjusting screw 37 is provided, by means of which

the block 31 may be moved between the ways 32 on the arm 33. The screw 37 is received in a threaded opening 38 extending through the block 31, and an unthreaded portion 37a at one end of the screw is supported in an opening provided in a plate 39 secured at the upper end of the arm 33. The screw 37 is held against longitudinal movement in the plate 39 by means of a collar 40 and a cap 41, enclosing the end of the screw. The cap 41 provides a squared tool-receiving portion 42, accessible through an opening 43 in the table 1, so that the screw 37 can be readily turned to cause shifting of the block 31 on the arm 33, and thereby change the position of the roller 29 in the raceway 28 of the 15 segment 23.

As previously pointed out, the raceway 28 of the segment 23 extends at an angle to the pivotal axis of the segment, and the angle is such that the raceway 28 is exactly parallel to the ways 32 20 of the arm 33 when the parts occupy the position of Fig. 1. In this position, the cam roll 36 is nearest the axis of the cam 26, the segment 23 is at one end of its throw, and the spindle 4 occupies such a position that the space between 25 the winding pin 11 and the winding arbor 10 is in exact alignment with the wire guide 9. Consequently, when the screw 37 is turned to cause shifting of the block 31 for the purpose of varying the number of revolutions made by the spindle 4 during one complete revolution of shaft 21, no movement is imparted to the segment 23, and the arbor 10 and pin 11 remain stationary, in readiness for the feeding of wire at the start of the operating cycle of the machine. As long as 30 the raceway 28 remains parallel to the ways 32, such adjustments can be made at will, and the length of the raceway 28 is such that the throw 35 of the segment 23 can be varied to cause the winding of springs having from one to thirty convolutions.

Let it now be assumed that the adjusting block 31 has been initially set to produce springs containing an intermediate number of convolutions between the maximum and minimum obtainable, 45 as for example, fifteen, and it is desired to produce springs having one more coil. It is then only necessary to turn the shaft 27 so that the parts occupy the position of Fig. 6, with the cam roll 36 farthest removed from the axis of the 50 shaft 27. The roll 29 on the block 31 has then swung the segment 23 to the left from the position of Fig. 1, so that the winding spindle 4 is at the other extreme of its movement, with a predetermined number of coils wound on the arbor 55 10. It is obvious that the raceway 28 is then no longer parallel to the ways 32 on the cam roll arm 33, so that turning of the adjusting screw 37 to shift the block 31 away from the pivotal axis of the segment 23 will actually result in turning the segment 23 farther to the left. Therefore, turning the adjusting screw 37 will have the result of turning the arbor 10, so that the machine operator can actually see another coil formed on the spring, should it be desired to add 60 another turn. When such an adjustment has been made, as for example to increase the number of coils from fifteen to sixteen, continued operation of the machine will result in the production of springs with the desired number of 65 coils, without further adjustment of any other parts. By reason of the above described relation between the raceway 28 on the segment and the ways 32 on the cam roll arm, it is possible to make basic adjustments to wind more or less 70 75 coils.

coils in a spring, without turning the arbor 10, and to make minor adjustments to increase the number of coils on a spring already formed, by actually turning the arbor to see that the desired adjustment has been made.

In order to reverse the direction of winding by the arbor 10, the gear 5''' may be turned around so that its hub will space its teeth from gear 5' on shaft 20, as shown in Fig. 14. A gear 5'', 10 with teeth wide enough to mesh with both gears 5' and 5''' is then mounted on a stud so as to reverse the rotation of the spindle 4, as compared to Fig. 1.

As previously pointed out, movement of the 15 spindle head 2, accompanied by rotation of the arbor 10, will result in the coils of the spring being wound either close together or spaced apart in accordance with the degree of such movement, and there will next be described the mechanism 20 for controlling this movement to accurately determine the pitch of the springs being wound.

Pitch control mechanism

As previously pointed out, back and forth movement of the spindle head 2 on the ways 3 is accomplished by means of a pitch lever 6, one end of which is slotted at 44 to embrace a pin 45 carried by a block 46, see Fig. 1. The block 46 is mounted on a screw shaft 47, extending between 30 a pair of spaced lugs 48 provided by the spindle head 2, as best shown in Fig. 2. In setting up the machine, the block 46 is adjusted by turning the screw shaft 47 to determine the initial position of the arbor for the start of the coiling operation. The block is then clamped in the desired, 35 position by a bolt 49, which tends to draw together split portions of the block 46 upon the screw shaft 47. Movement of the spindle head 2 is then entirely dependent upon turning of the lever 6 to control the pitch of the spring being wound.

The opposite end of the pitch lever 6 is pivotally supported by a stud 50 carried by a bracket 51 overhanging the table 1, the length of the lever being such that a relatively small angular turning movement about the pivot 50 will result in a considerable rectilinear movement of the spindle head 2 at the free end of the lever. Turning movement is imparted to the lever 6 by means 45 of a roll 52 carried by a stud 53 intermediate the ends of the lever 6, the roll 52 being received in a track 54 provided by a pitch cam 55. The pitch cam 55 underlies the lever 6, and as best shown in the sectioned portion of Fig. 1, is pivoted at one end on a stud 56 carried by a pitch control slide 57.

As best shown in Fig. 7, the slide 57 is slidably mounted between ways 58 provided by a slotted base 59, the table 1 providing a slot 60 through which extends a lug 61, forming part of the slide 57. The lug 61 is connected by a link 62 to the upper end of the segment 23, as shown in Fig. 1, so that oscillatory movement of the segment 23 by the cam 26 is converted into reciprocatory movement of the slide 57. When the pitch cam 55 occupies a position in which the cam track 54 extends at an angle to the ways 58 for the pitch slide 57, as shown in Fig. 2, it is evident that movement of the slide 57 to the left, as viewed in Fig. 1, will result in the pitch lever 6 being turned about its axis to move the spindle head 2 on its ways 3, and so impart a certain degree of pitch to the coils being wound on the arbor 10. On movement of the slide 57 to the 70 right of the return swing of the segment 23, the

arbor 10 will be returned to its original position for the formation of the next spring.

In order to vary the amplitude of movement of the spindle head 2 and thus control the pitch of the springs being wound, the pitch cam 55 is angularly adjustable about its pivot 56 on the slide 57. To this end, the opposite end of the slide 57 carries a bracket 63 secured by screws 64, with a portion 63a overhanging the end of the cam 55, and spaced therefrom, see Fig. 1. 10 The bracket 63 has a center of curvature about the pivot 56 of the cam 55, and a similarly curved clamping strip 65 fits closely between the overhanging portion 63a and the upper surface of the cam 55. A number of studs 66 are threaded 15 through the portion 63a and serve to press the strip 65 against the cam 55, and so clamp it in any desired angular position about its pivot 56. Therefore, the cam 55 provides means for imparting the desired pitch to springs being wound 20 on the arbor 10, in either direction. Should it be desired to wind a flat spring with its convolutions all lying in the same plane, the cam 55 is clamped in position with the sides of the track 54 in exact parallelism with the ways 58, on which 25 the pitch slide reciprocates.

By reason of the direct connection of the pitch control slide 57 with the segment 23, axial movement of the arbor 10 is synchronized with its rotative movement, so that springs will be wound 30 with a uniform pitch for a given setting of the pitch cam 55. Furthermore, the angular adjustment of the cam 55 about the axis of rotation of the axial roll 52 on the pitch lever 6, provides for a wide range of pitch control. It is also apparent that movement of the roll 52 for a given setting of the cam 55 is substantially multiplied at the free end of the lever 6, so that a very small movement of the segment 23 and slide 57 can be translated into a considerably greater axial 35 movement of the arbor 10 to obtain the necessary pitch when winding springs of a very small number of coils.

In the preceding description, reference has 40 been made to the feeding of wire 7 by the rolls 8 at the start of the spring winding operation, when the arbor occupies the position of Fig. 3, and before the segment 23 is moved by the cam 26 to turn the spindle 4. Any such movement of the feed rolls 8 must be closely timed in the operating cycle, and the mechanism for driving the feed rolls 8 so that they will frictionally engage and feed the wire at just the proper time, will 45 next be described.

Feed roll mechanism

As best shown in Fig. 4, the shaft 27 carrying the cam 26 extends beneath the table 1, and carries at its other end a bevel gear 67 in mesh with a bevel gear 68 on a shaft 69 extending upwardly through the table 1. The shaft 69 is connected by bevel gears 70 to a cam shaft 71 extending across the table 1 at right angles to the drive shaft 27, as shown in Fig. 2. The shaft 71 is driven from a suitable source of power, such as an electric motor M, located in the base 25, as shown in Fig. 1. The motor M is connected by belts 72 and pulleys 73 to a shaft 74, connected by gearing 75 to teeth 76 formed on a circular portion of the cam 26. A lever 77, pivoted at 78, 70 provides an operating portion 77a, accessible from the front of the machine for turning the lever, and thereby operating a clutching device 79 associated with the pulley 73, as indicated in dotted lines in Fig. 2. Obviously, the shaft 27 carrying 75

the cam 26, could be driven directly from any source of power other than the motor, the main consideration being that the shaft 27 and the cam shaft 71 be so connected that they rotate 5 at the same rate of speed.

As best shown in Figs. 2, 8 and 9, the shaft 71 carries a cam 80, adapted to impart a reciprocatory movement to a slide 81 connected by a link 82 to an arm 83. The arm 83 is pivotally mounted 10 on a stud 84, carried by a bracket 85 surrounding a shaft 86, on which is mounted one of the feed rolls 8. The arm 83 provides a raceway 87 in which is received a roll 88 mounted on a stud 89 forming part of a block 90. The block 90 is 15 slidable between ways 91 extending longitudinally in a segment 92 pivotally mounted on a stud 93. The opposite end of the segment 92 provides teeth 94 in engagement with the teeth of a pinion 95 mounted on the feed roll shaft 86. As best 20 shown in Fig. 9, the shaft 86 also carries a gear 96 in mesh with a gear 97 mounted on a shaft 98 carrying the other feed roll 8. Movement of the segment 92 about its pivot 93 is caused by turning of the arm 83 about its pivot 84 in response to 25 reciprocatory movement of the slide 81 by the cam 80. Such movement of the segment 92 is transformed into rotative movement of the roll shaft 86, and the other roll shaft 98 is turned in unison therewith, in the opposite direction of 30 rotation by the gears 96 and 97.

The degree of rotative movement imparted to the feed rolls 8 depends upon the amplitude of the swinging movement of the segment 92, and such movement is in turn dependent upon the 35 position of the block 90 in the raceway 87. In order to shift the block 90, a screw shaft 99 is received in a threaded opening 100 in the block 90, with an unthreaded portion 99a turnable in a plate 101 at the end of the ways 91. The shaft 40 99 is held against axial movement by a collar 102 and an enlarged head 103 providing a squared tool receiving portion 104. By turning the shaft 99, the block 90 can be shifted to vary the throw of the segment 92 for a given amount of turning 45 movement of the arm 83 by the cam 80. Thus, the feeding of wire 7 by the rolls 8 can be closely controlled, so as to determine the length of wire that is fed past the arbor to provide one end portion of the spring that is subsequently wound by 50 rotation of the arbor 10.

As best shown in Fig. 9, the shaft 98 carrying the left-hand feed roll 8, is mounted in a bracket 105 pivoted at 106, so that the left-hand roll is capable of movement toward or away from the 55 stationary axis of the right-hand roll 8. A spring 107 connected at its ends to the bracket 105 and to a fixed part of the machine, serves to yieldingly maintain the bracket 105 against an adjustable stop 108, so that normally the rolls 8 are not 60 in gripping engagement with the wire 7, and the wire may pass freely therebetween during the winding operation.

In order to cause the rolls 8 to engage the wire with sufficient pressure for feeding, the shaft 71 65 carries a cam 109, with which cooperates a roll 110 yieldingly mounted on an arm 111 of the roll bracket 105. The arm carries a sleeve 112, within which is received a plunger 113, with the roll 110 rotatably mounted at the end of the plunger, 70 which extends through the sleeve 112. A spring 114 serves to yieldably maintain the plunger 113 in the position shown, wherein the roll 110 is just out of engagement with the peripheral portion of the cam 109. This normal position of 75 the roll 110 is determined by the adjustment of

the stop 108, cooperating with the bracket 105. As the shaft 71 rotates, a projection 109a of the cam 109 engages the roll 110 to force the plunger 113 inside the sleeve 112, thereby compressing the spring 114 and tending to turn the bracket 105 5 about its pivot 106. While the spring 107 resists turning of the roll bracket, the positive force under the cam 109 acting through the compressed spring 114 is sufficient to turn the bracket and cause the left-hand roll 8, as viewed in Fig. 9, to 10 press against the other roll 8 and so grip the wire between.

The cam 109 is so formed and so timed with respect to the cam 80, that the wire 7 is gripped between the rolls 8, just before movement of the 15 slide 81, acting through the arm 83 and segment 92, imparts rotative movement to the rolls 8. Therefore, when the rolls 8 rotate in unison in opposite directions, indicated by the arrows in Fig. 2, a predetermined length of wire will be fed 20 between the arbor 10 and pin 11. The rolls stop as the slide 81 comes to rest, whereupon the roll 110 leaves the cam projection 109a and the roll bracket 105 returns to its original position against the stop 108, with the wire no longer gripped between the rolls. The above described feeding of 25 the wire takes place while the arbor 10 is stationary, since at that time the roll 36 on the arm 33 is received in a dwell on the winding cam 26, as shown in Fig. 1. Thus, the feed of the stock 30 takes place at the start of the winding cycle, and the rolls 8 have released the wire by the time the segment 23 starts to move and thus impart rotative movement to the winding spindle 4. After the wire has passed between the released rolls 35 8 during the winding operation, the segment 92 is returned by the cam 80 to its starting position, but the rotation of the non-engaged rolls 8 has no effect on the wire 7, due to the provision of a pair of check rolls 115, which will rotate only in 40 the direction in which the rolls 8 turn for feeding.

As previously pointed out, rotation of the arbor 10 in one direction, results in winding a spring with a predetermined number of convolutions and of a given pitch, after which the arbor comes 45 to rest, due to another dwell on the winding cam 26. While the arbor 10 thus remains stationary, the tool 12 severs the completed spring from the wire where it leaves the guide 9, after which the tools 12 and 13 cooperate to bend the projecting 50 end of the completed spring by mechanism which will next be described.

Wire severing and end forming mechanism

As best shown in Figs. 10 and 11, the wire 55 guide 9 extends through a holder 116 supported by a bracket 116a, which also provides vertical guideways 117 for a pair of tool slides 118 and 119, mounted above and below the guide 9. The slides provide seats 118a and 119a for receiving 60 springs 120, bearing on a portion of the bracket 116, so that each slide is yieldingly held away from the guide 9. A lever 121 pivoted at 122 has one end bearing on the upper surface of the slide 118, while its other end carries a roll 123 yieldingly 65 maintained in engagement with the periphery of a cam 124 by the pressure of the spring 120. A lever 125, pivoted at 126, similarly co-operates with the lower surface of slide 119, with a roll 71 beside the cam 124.

The lower slide 119 carries the cutting tool 12, while the upper slide 118 carries the forming tool 13, and normally, the tools 12 and 13 remain in the retracted positions of Fig. 11, while a spring S is wound on the arbor 10, in the manner pre- 75

viously described. When the arbor 10 comes to rest with a spring wound thereon, the wire extends from the arbor 10 into the guide 9, between the tools 12 and 13. Continued rotation 5 of the cam shaft 71, with the spring winding and wire feeding instrumentalities at rest, then causes the cams 128 and 124 to move the tools 12 and 13 into the dotted line position of Fig. 11.

As the slides 118 and 119 move toward the 10 wire 7, the offset portion of the forming tool 13 engages the wire at a point between the wound spring S and the end of the guide 9, as the upwardly moving cutting edge of the lower tool 12 severs the wire at the guide 9. This severs the 15 wire from the wire stock and continued upward movement of the cutting tool 12 results in the projecting end portion of the spring engaged by the tools being bent around the offset portion of the then stationary forming tool 13. The cams 20 124 and 128 then permit the slides 118 and 119 to be moved away from the wire guide 9 by the springs 120, thereby retracting the tools 12 and 13, and leaving a completed spring S on the arbor 10 with one end formed, as indicated. Obviously, other types of cutting and forming tools 25 may be employed, without departing from the invention; for example, the tool slides 118 and 119 may be replaced by a multiple tool forming head surrounding the wire guide 9, such as is 30 shown and described in the copending application of Charles R. Bergevin, Serial No. 171,120, filed October 26, 1937. The completed spring is now ready to be moved from the arbor 10 by a stripping mechanism, which will next be described.

35 Spring stripping mechanism

As best shown in Figs. 12 and 13, the stripping finger 14 is mounted at the end of an arm 129, pivoted at 130 on a slide 131 movable in horizontal ways 132 provided by a bracket 133. The stripper arm 129 provides an extension 134 below the pivot 130, to which is connected one end of an operating link 135, having its other end connected to a lever 136. The lower end of the lever 136 is pivoted at 137, and a spring 138, connected at its ends to the lever 136 and to the bracket 133, serves to maintain the lever 136 in engagement 40 with a roll 139 on a multiplying lever 140. The lever 140 is pivoted at 141, and carries a roll 142 between the roll 139 and its pivot 141. The pull 45 of the spring 138 serves to maintain the roll 142 in engagement with a cam 143 mounted on the shaft 71.

With the parts occupying the position of Fig. 12, the link 135 exerts a thrust on the extension 134 of the stripper arm 129, so as to turn the arm 129 about its pivot 130, and thereby maintain the stripping finger 14 in a raised position entirely clear of a spring being wound on the arbor 10. The cam 143 is so timed that after a spring 50 has been wound on the arbor 10 and severed from the wire at the guide 9, a projection 143a engages the roll 142 and turns both levers 140 and 136 to the left, as viewed in Fig. 12. When this occurs, the pull of the link 135 first turns the arm 129 so that it extends substantially parallel to the arbor 10, with the finger 14 engaging the completed spring on the arbor. An adjustable stop 55 144 carried by the slide 131, limits turning movement of the arm 129, so that after the arm 129 engages the stop 144, further movement of the link 135 by the lever 136, results in movement of the slide 131 to the left. This causes quick removal of the completed spring from the arbor 10 by the stripping finger 14, even though movement

of the spring is accompanied by movement of the arbor 10 in the same direction, as the spindle head 2 is moved to return the pin 11 to the position which it occupies at the start of the winding operation.

5

Operation and adjustment of the machine

Having described the various mechanisms entering into the machine, its operating cycle will be briefly described, with reference to the form of the cam 26 of Fig. 1. Assuming that the cam roll 36 occupies the position shown the arbor 10 is then at rest, with the space between the winding pin 11 and the arbor 10 exactly in line with wire guide 9. Rotation of the drive shaft 27, and with it the cam shaft 71, then causes the rolls 8 to immediately grip the then stationary wire, and feed a predetermined length of wire past the arbor. The arbor remains at rest during this feeding, due to the dwell on the cam 26, at the start of the cycle. After the wire has been fed, turning of the segment 23 serves to rotate the arbor 10, accompanied by rectilinear movement of the spindle head 2, thereby winding a spring on the arbor, having a predetermined number of convolutions 20 and a given pitch. These operations occur while the segment 23 moves from the position of Fig. 1 to the position of Fig. 6.

At the end of the winding operation, the arbor 10 comes to rest, due to a second dwell on the cam 26, whereupon the cams 124 and 128 operate the tools 12 and 13 to cause the wire to be severed at the guide 9, and to cause the end of the spring to be formed. After the severance of a completed spring, the segment 23 moves in the opposite direction, thereby returning the spindle head 2 to its original position, and turning the arbor 10 in the opposite direction to the starting position, reversal of the arbor 10 being accompanied by operation of the stripping finger 14 to remove the completed spring from the arbor 10. This completes the operating cycle, leaving the parts in position for the commencement of another cycle.

As previously pointed out, the number of convolutions wound in a spring can be varied through a wide range, by turning the screw 37 to shift the block 31, with the parts occupying the position of Fig. 1, wherein the raceway 28 is parallel to the ways 32. If, after winding springs having a given number of convolutions it is desired to increase the length of the springs, such adjustment can be quickly made by moving the parts to the position of Fig. 6, wherein turning of the screw 37 will result in convolutions being added to the spring already wound, within the view of the machine operator. Variations in the pitch of the springs being wound are readily obtained by adjusting the angle of the pitch cam 55, with respect to the line of movement of the slide 57. In order to vary the amount of wire fed by the rolls 8, to provide for one end of the spring that is to be wound, the screw shaft 99 is turned to shift the block 90. Movement of the block 90 varies the radius at 50 which turning movement is imparted to the segment 92 for a given movement of the slide 81 by the cam 80, whereby very accurate control of the amount of wire fed by the rolls 8 is obtained.

70 We claim,

1. In a machine of the class described a rotatable winding arbor, a drive shaft carrying a cam, a gear member for rotating said arbor and an adjustable connection between said cam and gear member for imparting oscillatory move- 75

ment thereto and causing said arbor to make a predetermined number of revolutions in either direction of rotation for each revolution of said drive shaft.

5 2. In a machine of the class described a rotatable winding arbor, a drive shaft carrying a cam, a gear member for rotating said arbor, a pivoted arm actuated by said cam and an adjustable connection between said arm and gear member for imparting a predetermined degree of oscillatory movement to said gear member.

10 3. In a machine of the class described a rotatable winding arbor, a drive shaft carrying a cam, a gear member for rotating said arbor, a pivoted arm actuated by said cam, a connection between said arm and gear member for imparting oscillatory movement to said gear member and means for adjusting said connection to cause said arbor to make a predetermined number of 15 revolutions in either direction of rotation for each revolution of said cam.

15 4. In a machine of the class described a rotatable winding arbor, a drive shaft carrying a cam, a gear member for rotating said arbor, a pivoted arm actuated by said cam, a connection between said arm and gear member for imparting oscillatory movement to said gear member and means operable without moving said arbor for 20 adjusting said connection to vary the number 25 of revolutions made by said arbor for one revolution of said cam.

30 5. In a machine of the class described a rotatable winding arbor, a drive shaft carrying a cam, a gear member for rotating said arbor, a pivoted arm actuated by said cam, a connection between said arm and gear member for imparting oscillatory movement to said gear member and means operable in one position of said cam for adjusting said connection to vary the 35 number of revolutions made by said arbor for one revolution of said cam, said adjustment being accomplished without imparting rotative movement to said arbor.

40 6. In a machine of the class described a rotatable winding arbor, a drive shaft carrying a cam, a gear member for rotating said arbor providing a guideway, a pivoted arm actuated by said cam also providing a guideway, a connection between said arm and gear member movable in both guideways and means for adjusting said connection to vary the number of revolutions made by said arbor for a given throw imparted to said arm by said cam.

45 7. In a machine of the class described a rotatable winding arbor, a drive shaft carrying a cam, a gear member for rotating said arbor providing a guideway, a pivoted arm actuated by said cam also providing a guideway, a connection between said arm and gear member movable in both guideways and means for adjusting said connection to vary the number of revolutions made by said arbor for a given throw imparted to said arm by said cam, adjustment of said connection, when said guideways are in parallel relation and said arm is nearest the axis of rotation of said cam, being obtainable in the absence of angular movement of said arbor.

50 8. In a machine of the class described a rotatable winding arbor, a drive shaft carrying a cam, a gear member for rotating said arbor providing a guideway, a pivoted arm actuated by said cam also providing a guideway, a connection between said arm and gear member movable in both guideways and means for adjusting said connection to vary the number of revolutions made by

said arbor for a given throw imparted to said arm by said cam, adjustment of said connection, when said guideways are non-parallel and when said arm is farthest from the axis of rotation of said cam, serving to also impart angular movement to said arbor.

5 9. In a machine of the class described, a frame, a head movable on said frame, a winding arbor rotatably mounted on said head, a drive shaft, a gear member for rotating said arbor, a connection between said drive shaft and said gear member for imparting a predetermined degree of oscillatory movement to said gear member, a lever for imparting rectilinear movement to said arbor head and a connection between said gear member and said lever, whereby axial movement is imparted to said arbor simultaneously with its rotative movement.

10 10. In a machine of the class described, a frame, a head movable on said frame, a winding arbor rotatably mounted on said head, a drive shaft, a gear member for rotating said arbor, a connection between said drive shaft and said gear member for imparting a predetermined degree of oscillatory movement to said gear member, a lever for imparting rectilinear movement to said arbor head and an adjustable connection between said gear member and said arbor head actuating lever for controlling the amount of movement imparted to said arbor head for a 15 predetermined degree of rotative movement imparted to said arbor by the movement of said gear member.

20 11. In a machine of the class described, a frame, a head movable on said frame, a winding arbor rotatably mounted on said head, a drive shaft, a gear member for rotating said arbor, a connection between said drive shaft and said gear member for imparting a predetermined degree of oscillatory movement to said gear member, a lever for imparting rectilinear movement to said arbor head, a reciprocating slide connected to said gear member and an adjustable connection between said slide and said arbor head actuating lever to control the degree of pivotal 25 movement of said lever for a given amount of movement of said slide by said gear member.

30 12. In a machine of the class described, a frame, a head movable on said frame, a winding arbor rotatably mounted on said head, a drive shaft, a gear member for rotating said arbor, a connection between said drive shaft and said gear member for imparting a predetermined degree of oscillatory movement to said gear member, a lever for imparting rectilinear movement to said 35 arbor head, a reciprocating slide connected to said gear member, a track angularly adjustable on said slide and a connection between said arbor head actuating lever and said track for converting movement of said slide into pivotal movement of said lever to an extent determined by the setting of said track.

40 13. In a machine of the class described, a frame, a head movable on said frame, a winding arbor rotatably mounted on said head, a drive shaft, a gear member for rotating said arbor, a connection between said drive shaft and said gear member for imparting a predetermined degree of oscillatory movement to said gear member, a lever for imparting rectilinear movement to said 45 arbor head, a reciprocating slide connected to said gear member and a connection between said slide and said arbor head actuating lever located nearer the pivotal axis of said lever than the point of connection of said lever to said head.

14. In a machine of the class described, a frame, a head movable on said frame, a winding arbor rotatably mounted on said head, a drive shaft, a gear member for rotating said arbor, a connection between said drive shaft and said gear member for imparting a predetermined degree of oscillatory movement to said gear member, a lever for imparting rectilinear movement to said arbor head, a connection between said gear member and said arbor head actuating lever for converting oscillatory movement of said gear member into rectilinear movement of said head and an adjustable connection between said head and said lever to determine the initial position of said head and arbor. 5
15. In a machine of the class described, a winding arbor, means for imparting intermittent rotative movement to said arbor, a pair of rolls for receiving stock extending in the direction of said arbor, a gear member for imparting rotative movement to said rolls, a pivoted arm for imparting oscillatory movement to said gear member and an adjustable connection between said arm and said gear member for controlling 10 the amount of stock fed past said arbor by rotation of said rolls. 20
16. In a machine of the class described, a pair of rotatably mounted rolls, one of which is yieldingly supported to permit stock to pass freely between said rolls, means for imparting rotative movement to the other of said rolls, means for causing the first-named roll to frictionally engage said stock prior to rotative movement of the other roll in one direction of rotation to cause 25 feeding of said stock and means for releasing said first-named roll from the stock in advance of rotative movement of the other roll in the opposite direction of rotation. 30
17. In a machine of the class described, a pair of rotatably mounted rolls, one of which is yieldingly supported to permit stock to pass freely between said rolls, means for imparting rotative movement to the other of said rolls, means for causing the first-named roll to frictionally engage said stock prior to rotative movement of the other roll in one direction of rotation to cause 35 feeding of said stock, means for releasing said first-named roll from the stock in advance of rotative movement of the other roll in the opposite direction of rotation and means for checking movement of the stock in a direction opposite to its movement of feeding. 40
18. In a machine of the class described, a rotatable winding arbor, means for feeding stock past said arbor when the latter is stationary, means for imparting rotative movement to said arbor for winding a length of stock thereon in the form of a spring, said feeding means being displaced from the winding axis with a straight 45 length of stock extending from a spring wound on said arbor, tools operable in a vertical plane at right angles to the line of stock feed and means for operating said tools after a spring has been wound on said arbor to sever said straight length 50 of stock and bend the end of the spring still on said arbor. 55
19. In a machine of the class described, a rotatable winding arbor, means for feeding stock past said arbor when the latter is stationary, means for imparting rotative movement to said arbor for winding a length of stock thereon in the form of a spring, said feeding means being displaced from the winding axis with a straight 60 length of stock extending from a spring wound on said arbor, tools operable in a vertical plane at right angles to the line of stock feed and means for operating said tools after a spring has been wound on said arbor to cause one tool to first engage said straight length of stock and then cause the other tool to sever said stock and bend the free end of the spring still on said arbor around 65 said first tool. 70
20. In a machine of the class described, a rotatable winding arbor, means for feeding stock past said arbor, means for rotating said arbor to wind said stock thereon in the form of a spring, means for severing a spring from said stock, a stripper normally maintained out of engagement with a spring on said arbor and means for imparting a combined pivotal and rectilinear movement to said stripper to engage a spring on said 25 arbor and remove it therefrom. 80
21. In a machine of the class described, a rotatable winding arbor, means for feeding stock past said arbor, means for rotating said arbor to wind said stock thereon in the form of a spring, means for severing a spring from said stock, a stripper normally maintained out of engagement with a spring on said arbor, means for first imparting a pivotal movement to said stripper to engage it with the end of a spring on said arbor 35 and means for next imparting a longitudinal movement to said stripper to cause it to remove said spring from the arbor. 90
22. In a machine of the class described, a winding arbor, a pair of rolls for receiving stock extending in the direction of said arbor, means for imparting intermittent rotative movement to said arbor, in one direction, to cause it to wind said stock into a coil, means for imparting intermittent rotative movement to said rolls to feed said stock past said arbor in the intervals between successive stock winding movements thereof, and means for varying the degree of rotative movement of said rolls to control the amount of stock fed past 45 said arbor by rotation of said rolls. 100
23. In a machine of the class described, a winding arbor, a pair of rolls for receiving stock extending in the direction of said arbor, said rolls being normally free of said stock, means for imparting intermittent rotative movement to said arbor, in one direction, to cause it to wind said stock into a coil, means for frictionally engaging said rolls with said stock and rotating said rolls to feed a length of stock past said arbor when the latter is stationary, and means for varying 55 the degree of rotative movement of said rolls to control the amount of stock fed past said arbor by rotation of said rolls. 110
